HEALTH VIBRATOR

Filed Dec. 31, 1928

UNITED STATES PATENT OFFICE

HERBERT H. BUFFUM, OF PORTLAND, OREGON; JENNIE L. BUFFUM, EXECUTRIX OF
SAID HERBERT H. BUFFUM, DECEASED, ASSIGNOR TO HERSELF AS RESIDUARY
LEGATEE

HEALTH VIBRATOR

Application filed December 31, 1928. Serial No. 329,445.

This invention relates to exercising machines embodying a non-rotatory vibrator element such as a bar which may be grasped in the hands or to which the ends of a body strap 5 may be attached, together with means for imparting rapid oscillations to said bar transversely of its longitudinal axis.

The principal objects of my invention are to simplify such devices, to render them more 10 compact and durable and less costly, to make them quieter in operation, and to avoid or reduce the transmission of objectionable vibrations to the driving motor and its support.

To these ends, in the preferred embodiment of my invention hereinafter described, I employ a rapidly revolving wobble shaft upon which the vibrator bar is journaled and from which it receives a gyratory movement, and further provide a revolving weight for 20 counterbalancing the bar, together with means for varying the relative eccentricity of said weight and bar to locate their centers of gravity approximately at equal distances from the axis of gyration.

25 Of the accompanying drawings, Fig. 1 is a plan view, partly in section, showing a preferred embodiment of my invention.

Fig. 2 is a cross-section on the line 2—2 of Fig. 1.

30 Fig. 3 is a cross-section on the line 3—3 of Fig. 1.

In the drawings, 10 is a vibrator bar consisting of a central hub and a pair of arms projecting therefrom in opposite directions 35 and adapted to be grasped in the hands or to have attached thereto the ends of a body strap 11. The arms of said bar are formed with a series of spaced lugs 12 on their upper sides for positioning said strap ends at varying distances from the hub in order to obtain different amplitudes of movement. The bar being thus connected with the user, either directly or through the strap, is thereby held 40 from rotation.

45 13 is a wobble shaft mounted in anti-friction bearings 14 in the hub of bar 10, and placed at a slight angle to the axis of revolution of said shaft so that a gyratory movement will be imparted to the bar as said shaft

is rotated therein, and the arms of said bar will be transversely oscillated.

15 is a rotary cylindrical head having a reduced stem or shaft member 16 axially apertured and provided with a set-screw 17 55 whereby it is adapted to receive and be detachably secured to the shaft 18 of an electric motor 19. The axis of rotation of said motor shafts, coinciding with that of the head 15, constitutes the axis of gyration of the vibrator bar assembly including the wobble shaft.

Stem 16 has mounted thereon a counterbalance weight in the form of a wheel 20 secured in place by the set-screw 17, said wheel being formed with a recess 21 on the same 65 side of the axis of shaft 18 as the center of gravity of the vibrator bar assembly so that the center of gravity of wheel 20 will be on the opposite side of said axis and may be caused to counteract the unbalance produced 70 by the angularity of shaft 13 and the consequent eccentricity of the bar assembly.

The head 15 is transversely bored through on an axis perpendicular to the plane of the centers of gravity of the bar assembly and the counterbalance wheel, and in said bore is mounted a cylindrical pivot shaft or member 22 which is apertured transversely of its axis to receive the rear end portion of the wobble shaft 13, a blind or flush-head set-screw 23 being provided in one end of said pivot member for securing the wobble shaft thereto. A collar 24 is provided for spacing the inner bearing 14 of shaft 13 from the pivot member. 75 80

85 The inner extremity of shaft 13 has a projection 25 formed with opposite, slightly-convex faces against which bear the inner ends of a pair of blind screws 26, 27 threaded in holes formed in the head 15 transversely of the axis of rotation thereof and counter-bored at their outer ends to receive the heads of said screws, whereby the pivot member 22 and wobble shaft 13 may be fixed in the head 15 at different angles with reference to the axis of rotation of said head in order to effect 90 an accurate balancing of the center of gravity of wheel 20 against that of the bar assembly. I do not wholly restrict myself to this particular means of varying the relative eccen- 95 100

tricity of the vibrator bar assembly and the counterbalance weight.

By the mechanism described, my invention provides for imparting a gyratory movement to the vibrator bar 10 in a very simple manner, and it further provides for counteracting the unbalance of the bar assembly in substantially the exact degree required in order to avoid communicating objectionable vibrations to the motor 19 and its support. In manufacturing these vibrator bars 10 on a commercial scale, it is practically impossible to secure a uniform distribution of the metal in different individual bars. Consequently their centers of gravity will vary slightly, and no uniform angularity of the wobble shaft 13 which would produce an accurate balance in all cases could be obtained without undue expense. By means of the described adjustment, however, it is a comparatively simple matter to arrive at a satisfactory degree of balance in one or more trials, and this setting can be obtained at the factory where the machines are made so that they will go to the purchaser in a correctly balanced condition.

While I have described a preferred form of construction, it will be understood that the details may be variously modified within the scope of the appended claims.

I claim:

1. An exercising machine comprising a vibrator bar including a hub and arms extending therefrom in opposite directions, a looped body strap having its ends connected with the respective arms, a wobble shaft mounted to turn in said hub, and means for rapidly revolving said shaft on an axis inclined to the axis of the shaft.
2. An exercising machine comprising a head structure axially apertured to receive a motor shaft and provided with means for detachably securing it to the shaft, a wobble shaft carried by said head structure at an inclination to the axis of rotation of the latter, and a non-rotatory strap bar journaled on said wobble shaft transversely of the axis of rotation.
3. An exercising machine comprising a non-rotatory strap bar, means engaging its middle portion for imparting a gyratory movement thereto, means for counterbalancing said bar, and means for varying the relative eccentricity of said bar and the counterbalancing means.
4. An exercising machine comprising a non-rotatory strap element, a wobble shaft rotatably engaging its middle portion for imparting a gyratory movement thereto, a shaft member for revolving said wobble shaft, and a counterbalance carried by said shaft member.
5. An exercising machine comprising a non-rotatory strap bar, a wobble shaft engaging its middle portion for imparting a gyra-

tory movement thereto, a rotary weight for counterbalancing said shaft and bar, a rotary support for said shaft, and means for varying the inclination of the wobble shaft on said support.

6. An exercising machine comprising a non-rotatory vibrator element, a wobble shaft for imparting a gyratory movement thereto, a rotary head, a pivot member carrying said shaft and mounted to turn in said head for the purpose of varying the inclination of the shaft, and means for fixing said pivot member at different angles in the head.

7. An exercising machine comprising a non-rotatory vibrator element, a wobble shaft mounted to turn on said element for imparting a gyratory movement thereto, said shaft having an adjusting projection at its inner end, a rotary head, a pivot member carrying said shaft and mounted to turn in said head, and a pair of screws mounted in said head and bearing on opposite sides of said adjusting projection for fixing said shaft and pivot member at different angles in the head.

8. An exercising machine comprising a rotary head structure having a stem or shaft member, a counterbalance weight carried by said shaft member, a wobble shaft carried by said head structure at an angle of inclination to the latter's axis of rotation on the side of said axis opposite to the counterbalance weight, and a non-rotatory vibrator element journaled on said wobble shaft.

9. An exercising machine comprising a rotary head structure having a stem or shaft member axially apertured to receive a motor shaft, a counterbalance weight structure carried by said shaft member, a set-screw passing through said weight structure and shaft member for securing the two together and for detachably securing them upon the motor shaft, a non-rotatory vibrator bar counterbalanced by said weight and means on said head structure for imparting a gyratory movement to said vibrator bar.

10. An exercising machine comprising a massaging belt, a motor having a rotary shaft, and means for vibrating said belt, said means including a member adapted to engage the ends of said belt and a shaft operatively associated with said member, fixed to said motor shaft and inclined thereto.

11. An exercising machine comprising a two ended, elongated flexible element, a motor having a rotary shaft, and means for vibrating said element, said means including a shaft fixed to said motor shaft and inclined thereto, and a member attached to the ends of the flexible element, mounted on said inclined shaft, said inclined shaft being rotatable relative to said member to give said member a wobble movement.

12. In an exercising machine of the character described, in combination, a rotary shaft, an inclined shaft fixed thereto, a mas-

saging element, a member having outwardly extending arms adapted for attachment to the ends of said element, a central hub, and a ball bearing thrust member interposed between said hub and said inclined shaft.

5 In witness whereof I have hereunto set my hand this 22 day of December, 1928.

HERBERT H. BUFFUM.
